FIG. 4

UNITED STATES PATENT OFFICE

2,151,670

POLISHING MACHINE

Wallace H. Wood, Worcester, Mass., assignor to
 Norton Company, Worcester, Mass., a corpora-
 tion of Massachusetts

Application October 21, 1938, Serial No. 236,309

7 Claims. (Cl. 51—154)

The invention relates to abrading machines, and more particularly to a polishing machine for polishing spaced cylindrical portions on a work piece.

- One object of the invention is to provide a thoroughly practical polishing machine for polishing spaced portions on a completely assembled electric motor rotor shaft or the like. Another object of the invention is to provide a polishing machine in which the work piece, such as an assembled armature shaft, is supported to rotate on a flexible abrasive element which serves simultaneously to support and polish spaced cylindrical portions thereon.
- Another object of the invention is to provide such a machine with an open top electric motor stator which corresponds in size with the assembled armature and shaft to be polished and which serves to rotate the rotor shaft by its own power. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a perspective view of the improved motor rotor shaft polishing machine;

Fig. 2 is a fragmentary end elevation thereof on a reduced scale;

Fig. 3 shows a fragmentary end view, on an enlarged scale, of the improved polishing machine employing bonded abrasive elements instead of a flexible abrasive element;

Fig. 4 is a fragmentary sectional view taken approximately on the line 4—4 of Fig. 3; and

Fig. 5 is a fragmentary front elevation of the yieldable device which engages one end of the rotor shaft during the polishing operation to assist in the oscillatory movement of the rotor shaft during polishing.

One embodiment of the improved polishing machine for polishing spaced cylindrical portions on a work piece has been disclosed in the drawing, comprising a base 10 having a pair of upwardly extending brackets 11 and 12 each of which is provided in its upper surface with a semi-circular groove 13 which serve as supports for continuous strips of flexible abrasive paper or cloth 14 and 15 to support and abrade spaced cylindrical portions 16 and 17 of an assembled

electric motor rotor shaft 18 having a rotor 19 fixedly assembled thereon.

The strip of abrasive paper 14 is wound up on a reel 25 which is rotatably supported by means of an upwardly extending bracket 26 which is fixed to the base 10. The abrasive cloth or paper 14 passes over the upper surface of the bracket 11 so that when the rotor shaft 18 is set in place, the abrasive paper will conform to the semi-circular groove 13 so as to support and polish the portion 16 of the rotor shaft 18. A reel 27 which is rotatably supported by an upwardly extending bracket 28 fixed to the base 10 serves to wind up the used portion of the flexible abrasive cloth or paper and is arranged so that after each polishing operation or as frequently as is desired, the abrasive paper may be advanced to present a fresh abrading surface for the polishing operation. The reel 27 has one of its side plates formed with ratchet teeth 29 which are arranged to be engaged by a pawl 30 which is in turn supported by a bracket 31 fixedly mounted on the upwardly extending projection 28. By turning the ratchet teeth 29 in a counterclockwise direction (Fig. 1), the abrasive paper 14 may be advanced as desired.

The endless strip of abrasive paper 15 is similarly wound up upon a reel 35 which is fixedly supported in an upwardly extending bracket 36 on the base 10. The abrasive strip 15 passes around beneath the cylindrical portion 17 of the rotor shaft 18 and conforms with the semi-circular groove 13 in the projection 12. A reel 37 serves to wind up the worn portion of the flexible abrasive strip 15. This reel is rotatably supported by a bracket 38 which is fixedly mounted on the base 10. One of the side plates of the reel 37 is provided with ratchet teeth 39 which are arranged to be engaged by a ratchet pawl 40 supported by a bracket 41 fixedly mounted on the supporting bracket 38.

To attain the main object of the invention, an open top electric motor stator 50 is fixedly mounted on the base 10 of the machine and is positioned and arranged so that when the rotor 19 is set in position for a polishing operation, a desired and predetermined air gap will be provided between the periphery of the rotor 19 and the internal surface of the open top electric motor stator 50. Power is supplied from any suitable source, such as power lines 51. A line switch 52 serves to close the circuit to pass a current through the open top electric motor stator 50 so as to transmit a rotary motion through the rotor 19 to rotate the rotor shaft 18.

which is supported in operative abrading contact with the flexible abrasive elements 14 and 15. Thus, the rotor shaft 18 is polished or lapped while being powered by its own assembled rotor 19.

It is desirable to provide a relative oscillating movement between the rotor shaft 18 and the flexible abrasive elements 14 and 15. In the preferred form a motor driven oscillating mechanism is provided for producing an endwise oscillating movement of the rotor shaft 18 during the rotation thereof so as to prevent individual abrasive grains from the elements 14 and 15 from producing rings or scratches around the periphery of the cylindrical portions 16 and 17 during the polishing or lapping operation. This mechanism comprises an electric motor 60 which is provided with a worm 61 mounted on the end of its rotor shaft. The worm 61 meshes with a worm gear 62 which is fixedly mounted on a rotatable shaft 63. The shaft 63 is journaled in suitable bearings in the brackets 64 and 65 which are fixedly supported on the base 10. The shaft 63 carries a cam 66 which bears against a pivotally mounted rock arm 67 which is pivotally supported by means of a shaft 68 supported on the base 10. The rock arm 67 is provided with a projecting boss 69 which is arranged to engage the end of the rotor shaft 18.

In order to maintain the end of the rotor shaft 18 in engagement with the boss 69 during the reciprocation of the rotor shaft 18, a spring-pressed follower plunger 70 is slidably mounted in a bracket 71 which is fixed to the projecting member 11 and is arranged to engage the left-hand end of the rotor shaft 18 (Figs. 1 and 5). A spring 72 within an enlarged portion 73 of the bracket 71 surrounds a stud 74 which is formed integral with the follower member 70 and is interposed between the follower member 70 and the end of the opening in the enlarged portion 73. The compression of the spring 72 is sufficient to exert a pressure in a direction toward the right (Figs. 1 and 5) at all times to maintain the right-hand end of the rotor shaft 18 against the boss 69 of the shaft reciprocating mechanism. It will be readily apparent from the foregoing disclosure that when the motor 60 is started rotating, the cam 66 will rock the arm 67 and transmit an oscillating movement to the rotor shaft 18 during rotation thereof, thus producing a rotary polishing movement of the cylindrical portions 16 and 17 which are supported on the flexible abrasive elements 14 and 15 and at the same time causing a relative endwise movement between these portions and the abrasive elements to produce a fine polished surface on the completely assembled electric motor rotor shaft.

If desired, bonded abrasive elements may be utilized in place of flexible abrasive strips 14 and 15. As illustrated in Figs. 3 and 4, a pair of bonded abrasive elements 90 and 91 may be mounted on each of the supporting projecting brackets 11 and 12. This construction is identical on each of said brackets, consequently only the construction of the members supported on the bracket 11 is illustrated. The abrasive members 90 and 91 may be clamped in position on the outwardly extending projection 11 by means of set screws 92 and 93. The abrasive blocks 90 and 91 are preferably provided with an adjusting device to compensate for wear so that the axis of the portion 16 of the rotor shaft 18 may be maintained in the same position as the blocks wear away. In the preferred construction, as illus-

trated, the bonded abrasive blocks 90 and 91 are backed by wedge blocks 94 and 95 which may be adjusted. A screw 96 is provided which passes through a yoked portion 97 on the wedge block 94 and is screw threaded into the upwardly extending bracket 11. By manipulation of the screw 96, the wedge may be moved either toward the right or toward the left to either raise or lower the abrasive block 90 so as to position the work axis in the desired position for a polishing operation and also serves to compensate for wear on the abrasive blocks after the abrasive block has worn during use. Similarly, the wedge block 95 may be adjusted by means of a screw 98 which engages a yoked portion 99 on the end of the wedge block 95 and is also screw threaded into the member 11 so that adjustment of the screw 98 serves to cause an endwise adjustment of the wedge block 94.

Similar bonded abrasive sticks are provided on the upper surface of the projecting bracket 11 to engage, support and polish the cylindrical portion 17 of the rotor shaft 18.

The operation of this improved electric motor rotor shaft polishing machine will be readily apparent from the foregoing disclosure. A completely assembled electric motor rotor shaft is placed in position on the machine with the cylindrical portions 16 and 17 engaging the flexible abrasive strips 14 and 15, respectively, to support the shaft for a rotary motion on the brackets 11 and 12. The opposite ends of the rotor shaft 18 are engaged by the boss 69 and the spring-pressed follower 70. The line switch 52 is then closed to start rotation of the rotor 19 on the rotor shaft 18 to rotate the shaft 18 under its own power for a polishing operation. At the same time the motor 60 is set in motion to transmit a reciprocatory movement through the cam 66 and the rock arm 67 to oscillate the rotor shaft 18 in an axial or endwise direction during rotation of the shaft while the spaced cylindrical portions 16 and 17 are supported on the abrasive elements 14 and 15, respectively, as shown in Figs. 1 and 2, or on the bonded abrasive sticks, as illustrated in the modification shown in Figs. 3 and 4.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:-

1. In a polishing machine, an abrasive element which serves to support and polish a cylindrical portion on a work piece and means including an open top electric motor stator which surrounds a portion of said work piece to rotate the same.
2. In a polishing machine, a continuous flexible abrasive element, a supporting member having a work supporting surface thereon to support said abrasive so as to form an abrasive support for a work piece to be polished, and means including an open top electric motor stator which surrounds a portion of said work piece to rotate the same.
3. In a polishing machine, a pair of spaced work supporting members having partial cylindrical work supporting surfaces thereon, a continuous flexible abrasive element on each of said

surfaces which are arranged to support a work piece for a polishing operation, a rotor on said work piece, and an open top electric motor stator partially surrounding said rotor and which serves 5 to rotate said rotor and shaft for a polishing operation.

4. In a polishing machine, a pair of spaced work supporting members each having a partial cylindrical work supporting grooved surface thereon, a continuous flexible abrasive element passing over each of said surfaces and serving to support and polish a work piece supported thereon, a motor rotor on said work piece, an open top electric motor stator partially 10 surrounding said rotor and serving through said rotor to rotate a shaft for a polishing operation, and means to reciprocate said work piece axially during rotation thereof.

5. In a polishing machine, a pair of spaced work 20 supporting members each having a partial cylindrical work supporting grooved surface thereon, a continuous flexible abrasive element passing over each of said surfaces and serving to support and polish a work piece supported thereon, a 25 motor rotor on said work piece, an open top electric motor stator partially surrounding said rotor and serving through said rotor to rotate a shaft for a polishing operation, and means including

an electric motor and a cam rotated thereby to reciprocate the work piece axially during rotation thereof.

6. In a polishing machine, a pair of spaced 5 work supporting members each having a partial cylindrical work supporting grooved surface thereon, a continuous flexible abrasive element passing over said grooved surfaces and serving to support and polish spaced cylindrical portions on a work piece supported thereon, an open top 10 electric motor stator partially surrounding an enlarged portion of said work piece, and means to supply electric power to said stator to rotate said work piece.

7. In a polishing machine, a pair of spaced 15 work supporting members each having a partial cylindrical work supporting grooved surface thereon, a continuous flexible abrasive element passing over said grooved surfaces and serving to support and polish spaced cylindrical portions 20 on a work piece supported thereon, an open top electric motor stator partially surrounding an enlarged portion of said work piece, means to supply electric power to said stator to rotate said 25 work piece for a polishing operation, and means including a motor and cam to reciprocate the work piece axially during rotation thereof.

WALLACE H. WOOD.
